UNITED STATES PATENT OFFICE.

LOTHAR VON GRAVE, OF WALLINGFORD, CONNECTICUT, ASSIGNOR TO THE
H. L. JUDD & COMPANY, OF NEW YORK, N. Y.

DESIGN FOR A PICTURE-FRAME.

SPECIFICATION forming part of Design No. 23,218, dated April 24, 1894.

Application filed March 27, 1894. Serial No. 505,346. Term of patent 3½ years.

To all whom it may concern:

Be it known that I, LOTHAR VON GRAVE, a subject of the King of Prussia, residing at Wallingford, Connecticut, have invented and 5 produced a new and original Design for Picture-Frames, of which the following is a specification, reference being had to the accompanying drawing, wherein the figure shows a face view of a frame illustrating my design, 10 one-half only of said view being shown in full lines, the other half being shown in outline.

The essential features of my design, which will be hereinafter more fully described, consist in a central ornamental portion 15 rounded by a leaf-like openwork portion with chasing thereon, said leaf-like portion having openings extending in from the outer edge between the convolution thereof, and said

leaf-like portion extending in substantially pyramidal form at the top of the frame. 20

Reference being had to the accompanying drawing, *a* designates the central ornamental portion provided with an opening *x*, and *b* the surrounding openwork, leaf-like portion. Extending in from the outer edge between 25 the convolutions of this leaf-like portion are openings *c*. The convolutions or leaf-like portion extends up at the top of the frame into substantially pyramidal form *e*.

What I claim is— 30

The design for a picture frame, substantially as shown and described.

LOTHAR VON GRAVE.
